UNITED STATES PATENT OFFICE.

OZELLO R. HUNT, OF KENOSHA, WISCONSIN, ASSIGNOR TO THE SIMMONS MANUFACTURING COMPANY, OF KENOSHA, WISCONSIN, A CORPORATION OF WISCONSIN.

WIRE FABRIC FOR FOLDING BEDS.

SPECIFICATION forming part of Letters Patent No. 758,920, dated May 3, 1904.

Application filed September 17, 1902. Serial No. 123,704. (No model.)

To all whom it may concern:

Be it known that I, OZELLO R. HUNT, a citizen of the United States, residing at Kenosha, in the county of Kenosha and State of Wisconsin, have invented a new and useful Improvement in Wire Fabric for Folding Beds, &c., of which the following is a specification.

My invention relates particularly to fabrics for folding beds, sofa-beds, folding couches, &c.; and my primary object is to provide a fabric which can be cheaply manufactured, which will fold readily either transversely or longitudinally, and which will not sag unduly when in use.

15 The invention is illustrated in the accompanying drawings, in which—

Figure 1 represents a fragment of the frame of a sofa-bed or folding couch with the improved fabric attached; Fig. 2, a broken perspective view showing the manner in which the fabric folds on a sofa-bed, say; Fig. 3, a similar view showing how the fabric folds on a mantel-bed, say; and Fig. 4 a perspective view of a modified form of link which may 25 be employed.

The preferred construction is as follows:

A represents a portion of the frame of a folding bed, sofa-bed, or the like, and B a fabric or bed-bottom attached thereto. The fabric 30 comprises links B', extending longitudinally of the article of furniture, assuming it to be used as a bed, and links B², connecting the links B' at their ends. Coil-springs B³ connect the ends of the fabric with the adjacent frame members, and additional links B² connect the lateral margins of the fabric with the adjacent frame members. As indicated, each link B' comprises a loop or ring B⁴, substantially parallel members B⁵, extending there- 35 from and lying side by side, and a hook B⁶ at the extremities of the members B⁵. Each link is preferably formed from a single piece of wire, bent as indicated. Each link B² comprises a short piece of wire with closed hook 40 ends. The links B' are arranged in parallel series with the hooked ends extending in a common direction, the hook of each link engaging the eye of the adjacent link. The rows 45

of links thus formed extend parallel to each other with the links arranged in rows transversely, whereby the eyes of the links are brought into alignment transversely. The longitudinal rows are connected by hooking the transversely-extending links B² upon the eyes B⁴. Thus it will be observed the strain 50 upon the fabric is transmitted in direct lines both longitudinally and transversely and there is no possibility of any part of the wire “drawing through” or straightening out, to the detriment of the bed-bottom. 55

Fig. 4 illustrates a link similar to the links B', but having its parallel members twisted upon each other adjacent to the eye. This link may be employed where a particularly strong construction is desired, but is unnecessary for ordinary purposes. 60

Assuming the fabric to be applied to a sofa-bed or folding couch with the longitudinal rows of links extending parallel with the lines of folding, the folding of the fabric occurs as 70 indicated in Fig. 2. On the other hand, assuming the fabric to be applied to a mantel-bed with the longitudinal rows extending perpendicular to the line of folding, the folding of the fabric occurs as indicated in Fig. 3. 75

An advantage incident to this construction is that the fabric may be folded into small space for shipping purposes, the folding being accomplished in both directions. A further advantage is that by forming the longitudinal links of folded wire small-gage wire 80 may be employed without sacrificing the required strength, resulting in springiness in the links themselves. Moreover, the construction provides the maximum bearing-surface for the mattress, and the surface is an even one, thereby prolonging the life of the mattress. To form the links of single lengths of wire would necessitate an increase in their number or the use of a heavier and stiffer wire, 85 both of which expedients would be objectionable for evident reasons. It should be remarked that the strain upon the fabric is transmitted chiefly in longitudinal lines and that so far as the fabric itself is concerned it 90 is unnecessary to connect it to the frame at 95

its lateral edges, although to do so enables a smaller angle-bar to be used in the frame, as the frame is thereby stayed against flexure.

Changes in details of construction within 5 the spirit of my invention may be made. Hence no undue limitation should be understood from the foregoing detailed description.

What I regard as new, and desire to secure by Letters Patent, is—

10 1. A longitudinally and transversely foldable wire fabric composed of a plurality of similar members arranged in a common direction in parallel series and ranged in transverse rows, each member formed of wire centrally bent to provide a contracted and practically closed eye and two substantially parallel straight portions with downturned hooks at 15 their free ends, adjacent hooks and eyes being in direct engagement, and a plurality of uniform links comprising single-length wires with downturned hooked extremities engaging the eyes of said first-named members, for 20 the purpose set forth.

of said first-named members, for the purpose set forth.

2. A longitudinally and transversely foldable wire fabric composed of a plurality of similar members arranged in a common direction in parallel series and ranged in transverse rows, each member formed of wire centrally bent to provide a contracted and practically closed eye and two substantially parallel straight portions with downturned hooks at 25 their free ends, adjacent hooks and eyes being in direct engagement, and a plurality of uniform links comprising single-length wires with downturned hooked extremities engaging the eyes of said first-named members, for 30 the purpose set forth.

OZELLO R. HUNT.

In presence of—

A. C. KITTELESON,
ALBERT D. BACCI.
